United States Patent Office.

ALBERT W. JOHNSON, OF NEW YORK, N. Y.

Letters Patent No. 81,786, dated September 1, 1868.

IMPROVED WHIP-HOLDER.

The Schedule referred to in these Letters Patent and making part of the same.

TO ALL WHOM IT MAY CONCERN:

Be it known that I, ALBERT W. JOHNSON, of the city, county, and State of New York, have invented certain new and useful Improvements in Holders for Whips, &c.; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

The holder, to which this invention relates, is more especially designed for whips, but it may be adapted for many articles, such as billiard-cues, umbrellas, canes, &c.

And this holder consists of self-closing jaws, of suitable shape and size to grasp the whip, &c., for holding which the holder is adapted, in combination with a rest for the end of the whip, &c., which is so connected with the said jaws, as, when pressure is brought to bear upon it to open the said jaws to receive the whip when releasing the pressure, the jaws will close themselves about the whip, holding it in position.

In the accompanying plate of drawings my improved holder for whips, &c., is illustrated—

Figure 1 being a side view of the same.

Figure 2, a plan or top view.

Figure 3, a central vertical section, taken in the plane of the line *x x*, fig. 2; and

Figure 4 a transverse section, taken in the plane of the line *y y*, fig. 3.

A, in the drawings, represents my improved holder, to which B B are the two jaws. These jaws, in the present instance, are made of a semicircular shape, but they may be made of other and various forms. At their ends C they pass by each other, and at their other ends, D, are each fixed to sleeves or tubes, E and F, the one jaw to one sleeve, E, and the other to the other sleeve, F. These tubes or sleeves are connected with each other, and are placed, the one within the other, around a centre-shaft or rod, G, the whole being enclosed in a case, H, of suitable form.

The shaft G projects and moves through the ends I of the case H, and within the case, between its two ends, is provided with a pin or stud, J, that projects through slots K in the two sleeves, E and F, into a slot, L, made in the case H. The slots K of the sleeves E and F extend in the direction of their length partially around the same, forming spiral slots, passing in opposite directions, so that the said sleeves, when the shaft G is drawn through them, will be turned in opposite directions.

The slot L of the case H is straight, and acts as a guide to the pin. O, a spiral spring confined in case H, between its lower head and a collar on centre shaft G. This spring is compressed by drawing the shaft G down in the case, and by its reaction raises the shaft to its original position.

Fixed to the lower end of the shaft G is a conical-shaped cup, M, extending out in the same vertical plane with the jaws B.

By pressing on the cup M, the shaft G is pulled down through the case H, turning by its pin J acting in the spiral slots K of the sleeves or tubes E and F, thus opening the jaws B from each other.

N, ear-pieces, fixed to case H. These ear-pieces are provided for fastening the case in position upon a carriage, if the device is to be used as a whip-holder or socket.

To place a whip in the holder, first place it by its end in the socket or cup M, when, forcing down such socket M, the jaws B are opened, allowing the whip to be brought into them, when, releasing the pressure upon the socket M, the jaws, by the action of the spring O, are then closed about it, holding and securing it in position.

By my improved holder, a whip can be held most securely and firmly, and by a proper construction of the holding-jaws B, without injuring the finish of the whip in the least, either when inserting or removing it or while in the holder.

The cup or socket M may be made of various shapes or styles, and in lieu of a socket a simple plate may be used.

Having thus described my improvements, what I claim as my invention, is—

1. A holder for whips, &c., composed of jaws B, in combination with a rest, M, or their respective equivalents, connected together so as to be operated and to operate substantially in the manner described.
2. The jaws B, sleeves E F, centre-shaft G, spring O, and rest M, when all constructed and arranged together for operation substantially as described.

ALBERT W. JOHNSON.
